UNITED STATES PATENT OFFICE.

JOHN E. YOST, OF ARKANSAS CITY, KANSAS.

BOY'S WAGON.

1,006,708.

Specification of Letters Patent. Patented Oct. 24, 1911.

Application filed June 5, 1911. Serial No. 621,238.

To all whom it may concern:

Be it known that I, JOHN E. YOST, a citizen of the United States, residing at Arkansas City, in the county of Cowley and State of Kansas, have invented a new and Improved Boy's Wagon, of which the following is a specification.

This invention relates to that class of wagons generally used by boys for coasting and it has for its object to provide a wagon of the general character stated that can be economically made and in which the several parts are especially designed so that the user can easily manipulate the same and readily control the direction of the wagon while running, either on the level or coasting.

My invention also has for its purpose to provide an improved construction of wagon, of the kind stated, having special provision for holding the user in an upright position standing on one foot while kicking the wagon forwardly with the other foot and in such manner that he can support himself while controlling the direction of running.

With other objects in view that will hereinafter appear, my invention comprises the improved construction of boys' wagons hereinafter fully explained, specifically pointed out in the appended claims and illustrated in the accompanying drawings, in which:

Figure 1, is a perspective view of my invention that also shows how it is used while coasting. Fig. 2, is a front elevation of the wagon with the tongue thrown back. Fig. 3, is a plan view of the front end of the wagon. Fig. 4, is a transverse section thereof taken on the line 4-4 on Fig. 3. Fig. 5, is a longitudinal section the tongue being shown at the forward or wagon pulling position, in dotted lines. Fig. 6, is a perspective view that shows the front gearing of the wagon and the combined pulling and steering tongue that cooperates therewith. Fig. 7, is a detail perspective view showing the swivel tongue bearing separated. Fig. 8, is a detail view of a modified construction of the means for connecting the tongue and the running gear.

In carrying out my invention, I take the conventional shape of boys' wagon body and provide it with a rear extension 1 that has a standing platform 10 located below the bottom 11 of the wagon body and preferably near the ground, so the boy, while standing on the platform, with one foot, can easily

kick the wagon forwardly with the other foot, see Fig. 1.

The rear end of the wagon carries the rear axle 2 that is provided with the usual wheels 20, while the front end of the wagon is mounted on a pair of caster wheels 3-3 each journaled in a U shaped housing 30 to the upper end of which is secured a king bolt 31, the said bolts 31 working in the vertical sockets 32 in the outer front corners of the wagon body, they being removably held therein for economy in manufacture and for readily separating the parts for packing and shipping. Each housing 30 has a rearwardly extended and downwardly curved member 33 and the two members 33 are joined by a cross bar 34 that connects the two front wheels to cause them to move together during the steering adjustment.

In the preferred construction, and as best shown in Figs. 3 and 6, the cross bar 34 has a rack 35 for engaging with a cog gear 36 on the tongue 4, the front end of which is swivelly and rotatably joined to the front cross frame 50, that includes the upwardly extended side members 51-51 pendently secured to the bottom of the wagon body. The cog 36 is preferably a corrugated sheet metal plate that is bent around the tongue and is made fast thereto in any approved manner. The front end of the tongue has a ball head 41 for engaging the ball socket 42 in the bracket 43 that consists of two half sections each formed with a half screw shank 44, the two parts being so shaped that when slipped over the ball head 41 the bracket can be readily screwed down through the cross member 50 and secured therein by the lock nut 45.

15 designates a longitudinal slot in the wagon bottom that extends back some distance from the front end thereof and the said slot receives, forms a guide for, and laterally braces the tongue 4 when it is thrown back to the position shown in Figs. 1, 2 and 3.

Fig. 8 illustrates a modified means for connecting the tongue with the running gear and the same embodies a straight cross bar 34 formed with an aperture 38 centrally of the said bar, and the tongue has a pendent rod, 48 that slips down through the said aperture. In this latter form the rod 48 acts as a crank member for shifting the bar 34 when the tongue is rotated. By reason

of connecting the tongue to the wagon body, as shown, and providing the said body with a central longitudinal slot it is obvious a true guide for the tongue when it is swung back, is provided, since the fore part of the said tongue rests within the said slot, thus keeping the handle head in the central line of the wagon and in a convenient position for grasping, the side walls of the wagon body slot serving to brace the said tongue and thereby giving the boy a firm bearing or support for his body while manipulating the said tongue to steer the wagon. By providing the tongue with a cog gear for the same while turning the tongue in its ball and socket joint engages the rack on the bar 34 and thereby renders the steering operation, not alone positive and easy, but provides a substantial brace or support for the user, it being apparent that a slight rotation of the tongue in either direction will carry both of the front wheels to the directions desired.

While I have shown and described but a single modification of the preferred construction, it is obvious other modifications and variations of the said preferred constructions may be made without departing from my invention or the scope of the appended claims.

What I claim is:—

1. In a boy's wagon, a wheeled body including a free front short turn gear, a draft tongue connected to the front of the body and swingable back over the body, and means for operatively connecting said tongue with said short turn gear when said tongue is brought back over the body.

2. In a boy's wagon, a wheeled body including a free front short turn gear, a draft tongue connected to the front of the body and swingable back over the body, means for operatively connecting said tongue with said short turn gear when said tongue is brought back over the body, said body having a recess to receive and brace said tongue when swung back over the body.

3. In a boy's wagon, a wheeled body including a free front short turn gear, a draft tongue connected to the front of the body and swingable back over the body, means for operatively connecting said tongue with said short turn gear when said tongue is brought back over the body, and a rear step on said body adjacent to which said tongue is adapted to project to be grasped by the operator.

4. In a boy's wagon, a wheeled body including a front short turn gear, a draft tongue connected to the front of the body and swingable back over the body, means for operatively connecting said tongue with said short turn gear when said tongue is brought back over the body, said body having a recess to receive and brace said tongue when

swung back over the body, and a rear step on said body adjacent to which said tongue is adapted to project to be grasped by the operator.

5. In a boy's wagon, a wheeled body including a free front short turn gear, a draft tongue connected to the front of the body and swingable back over the body, means for operatively connecting said tongue with said short turn gear when said tongue is brought back over the body, said operative connection between said tongue and said short turn gear including means carried by said tongue for turning said short turn gear as said tongue is bodily rotated.

6. In a boy's wagon, a wheeled body including a front short turn gear, a draft tongue connected to the front of the body and swingable back over the body, means for operatively connecting said tongue with said short turn gear when said tongue is brought back over the body, said body having a recess to receive and brace said tongue when swung back over the body, a rear step on said body adjacent to which said tongue is adapted to project to be grasped by the operator, said operative connection between said tongue and said short turn gear including means carried by said tongue for turning said short turn gear as said tongue is bodily rotated.

7. A wagon having a pendent platform at the rear end and a free running gear at the front end, a tongue having a hinged connection with the said body whereby it can be extended backwardly over the wagon body, means on the said wagon body for holding the tongue from lateral play, and other means operated by the tongue while engaging the said first named means for controlling the running gear.

8. In a wagon having rear wheels and a free front steering wheel, said steering wheel having a king bolt bearing on the wagon body, a tongue hinged to swing forwardly and backwardly in the longitudinal plane of the wagon body, the said tongue being rotatably mounted, and means co-operatively connectible with the wagon and the front steering wheel for controlling the movement of the said steering wheel, said means being operated by the rotary movement of the tongue.

9. In a wagon having a free steering wheel at the front end and a rotatable tongue hinged to the wagon body, and connections for joining the steering wheel and the tongue for controlling the movement of the steering wheel as the tongue is rotated.

10. In a boy's coasting wagon, a body having a pendent platform at the rear end, and a longitudinal slot in the front end of the body, fixedly supported rear wheels for the body, a caster wheel at each front corner of the body, a member connecting the two caster

wheels to cause them to move in unison, said member having a rack face and a tongue member rotatably mounted in the slotted bottom, said member having a cog surface 5 for engaging the rack on the caster wheel connecting bar whereby to oscillate the said bar as the tongue is rotated.

11. In a wagon, a wheel body including front wheels mounted to freely turn on 10 vertical axes, means connecting said wheels to turn together, a relatively fixed bracket member supported beneath said body, a

tongue connected to said bracket member and swingable back over said body, means for operatively connecting said tongue with 15 said pivoted wheels to cause said wheels to be turned on their pivots as said tongue is turned on its axis, substantially as shown and described.
